UNITED STATES PATENT OFFICE.

ALFRED SMALLWOOD, OF HIGHGATE, LONDON, ENGLAND.

FURNACE FOR TREATING ARTICLES.

1,312,928.

Specification of Letters Patent.

Patented Aug. 12, 1919.

Application filed September 19, 1916. Serial No. 121,074.

To all whom it may concern:

Be it known that I, ALFRED SMALLWOOD, a subject of the Kingdom of Great Britain, residing at 42 Hargrave Park, Highgate, 5 London, N., in the county of Middlesex, England, have invented certain new and useful Improvements in or Relating to Furnaces for Treating Articles, of which the following is a specification.

10 This invention comprises certain improvements in or relating to furnaces for heating, hardening, tempering, annealing, carbonizing and other processes.

According to the present invention the 15 heating chamber of the furnace is provided with a removable bung or closure member, said bung or closure member being adapted to be displaced to permit of the article or articles contained in the heating chamber 20 being lowered therefrom below the level of the bung.

The present invention further comprises a furnace having a bung or closure member and in which mechanical means are provided for lowering and raising said bung or closure member and also for permitting of a lateral movement of said bung or closure member. With this object in view the bung or closure member may be carried by a truck 25 or carriage adapted to run on carrier means, such carrier means being adapted to be raised or lowered.

In order that this invention may be clearly understood and readily carried into practice, 30 reference may be had to the appended explanatory sheets of drawings, upon which:—

Figure 1 is a sectional side elevation of my device.

Fig. 2 illustrates certain details of construction of the guide members utilized in connection with the sealing member, taken on line A—A of Fig. 1.

In my present invention at the bottom a heating chamber is closed by a bung adapted 45 to be removed in such a manner as to permit of the goods being lowered from the heating chamber into an oil or other bath, as for instance for tempering purposes.

The bung is adapted to be readily removable and is conveniently of a character sufficiently substantial to take the weight of the goods, which latter are advantageously suspended in the heating chamber, but may have to rest upon the bung.

With this object in view the bung *r*, Fig. 55 3, may be carried by a truck *s* adapted to be moved laterally or horizontally on rails *t*.

The rails *t* are adapted to be raised and lowered, as for instance by being mounted with links *u*, *u* to be displaced by a parallel 60 motion, the links being operated in any suitable manner, as for instance by a worm *v* engaging with a quadrant *w* fixed co-axially with one of the links *u*.

Between the bung *r* and the lower extremity of the heating chamber, a sand or other seal *x* is incorporated, and in separating the bung from the heating chamber it is first necessary to lower the bung to withdraw the latter from the lower part of the heating 70 chamber and also to separate the sand or other seal *x*, after which the carriage *s* carrying the bung is displaced laterally along the rails *t*, by any approved mechanism. Guides *z* and *z'* are provided to maintain 75 the bung *r* and carriage *s* in central relationship to the heating chamber *a* during its vertical displacement.

Below the level at which the carriage works a tank *2* is incorporated so that after the 80 removal of the bung by the carriage, the goods contained in the heating chamber can be lowered into the tank, which may, for instance, contain oil. The bung operating mechanism is contained in a space which is 85 sealed from the atmosphere, and the opening in this space permitting of access to the tank is adapted to be sealed. For this purpose a sealing member *3* in the nature of a cylinder having near its upper edge one 90 portion *4* of an annular sealing device adapted to coöperate with the other portion 5 of such sealing device provided around the outlet offering access to the tank *2*, is adapted to be lowered into the tank in such 95 a manner that when the sealing parts *4*, *5*, are in coöperation, the lower part of the cylinder *3* dips below the surface of liquid in the tank, and thereby effectively closes the space containing the bung operating mechanism from the space containing the tank and therefore from the atmosphere, while permitting of access to the contents of the tank.

The tank is contained in a pit and is adapted to be moved laterally, as for instance by being provided with anti-friction members adapted to work upon runners. Lateral displacement of the tank is permitted by the 100 105

cylindrical sealing member 3, which may be raised clear of the upper surface or edge of the tank 2 to permit of the lateral displacement of the latter. Suitable guiding means 5 are provided for guiding the sealing member 3 in its vertical movements, and such movements may be imparted to said sealing member 3 by any suitable mechanism, such as a cord 8 carried around suitably disposed 10 pulleys to a point for convenient operation.

The tank for containing oil may have a hollow wall 6 which may contain water for cooling purposes.

When the bung is removed from under 15 the article the latter is supported by a crane by means of any suitable holding device, passing into the top of the furnace chamber.

It is by this means that the article is lowered into the oil bath.

What I claim as my invention and desire to secure by Letters Patent is:—

A furnace having a closure member, mechanical means for lowering and raising said closure member, such closure member being adapted to be carried by a truck or carriage capable of running on carrier means, a stationary part, links connecting such carrier means with said stationary part, the said carrier means being adapted to 25 30 be displaced by a parallel motion.

In witness whereof I have hereunto set my hand.

ALFRED SMALLWOOD.
